UNITED STATES PATENT OFFICE.

LYMAN C. MARTIN, OF WINFIELD, KANSAS.

CHURN.

SPECIFICATION forming part of Letters Patent No. 728,262, dated May 19, 1903.

Application filed December 17, 1902. Serial No. 135,620. (No model.)

To all whom it may concern:

Be it known that I, LYMAN C. MARTIN, a citizen of the United States, residing at Winfield, in the county of Cowley and State of Kansas, have invented certain new and useful Improvements in Churns; and I do hereby declare the following to be a full, clear, and exact description of the invention, such as will enable others skilled in the art to which it app pertains to make and use the same.

My invention relates to churning; and it consists of certain novel features of combination and construction of parts, the preferred form whereof will be hereinafter set forth.

The object of my invention, among others, is to provide a churn which may be very cheaply constructed of any preferred and suitable material which will be found to be reliably efficient in the production of butter with a minimum expenditure of time and labor.

Other objects and advantages will be hereinafter made clearly apparent, reference being had to the accompanying drawings, which are made a part of this application, and in which—

Figure 1 is a perspective view of my invention complete ready for use. Fig. 2 is a longitudinal central section of the churn-body.

Fig. 3 is a detail view, in side elevation, of the interior chamber or reservoir.

For convenience the various details of my invention and accessories required to illustrate a practical application thereof to use will be referred to by numerals.

Referring to the drawings, 1 indicates a pair of rockers, to which are secured a plurality of standards 2, carrying at their upper ends the frame-section 3, upon which my churn-body 4 is carried and secured in any preferred way, as by a band or strap 5.

The churn-body is preferably cylindrical, though other form of outline in cross-section may be adopted. In the present instance I have provided the body portion 4 at one end with the threaded neck 6, having a cap 7 adapted to fit said neck and be turned home thereon, so as to produce a non-leaking joint.

The cap 7 is provided centrally with a central opening, also threaded, as indicated by the numeral 8, and adapted to fit around the

threaded neck 9 of the interior water-reservoir 10.

The water-reservoir 10 is of sufficient length to reach throughout the interior of the body 4 from end to end, the inner end of the reservoir being received by the retaining-flange 11, which is secured to the inner end of the body 4, as more clearly shown in Fig. 2.

The inner end of the water-reservoir 10 is of such diameter as to snugly fit in the flange 11, and said reservoir 10 is provided with the apertures 12, adapted to be brought into or out of registration with the apertures 13, provided in the flange 11, for a purpose hereinafter set forth.

The inner end of the reservoir 10 is also provided with the cushioning-spring 14, adapted to bear directly against the inner face of the end of the body 4, as more clearly shown in Fig. 2. It will therefore be seen that the flange 11 and the threaded neck 8 will secure and reliably hold the reservoir 10 concentrically within the body 4, and the milk is therefore adapted to occupy the annular space thus afforded around the reservoir 10, and in order that a maximum degree of agitation may be imparted to the milk I provide the annular collars or flanges 15, there being any preferred number of said flanges, which are fixedly secured to the reservoir 10 in any desired way.

The said flanges 15 may also be provided, if desired, with a plurality of apertures 16 throughout their entire radial extent in order that the milk and cream may pass freely therethrough and induce a greater degree of agitation of the same.

The churn-body 4 is also preferably provided upon its under side with the cleat-sections 17, adapted to rest between the cross-bars 18, and thus hold the body portion 4 from longitudinal movement when placed upon the carriage.

A suitable opening 19 is also provided in the upper portion of the body-section 4, said opening having the cap-section 20, as shown, whereby the contents of the churn-body 4 may be readily examined from time to time or introduced therethrough.

The cap is also provided with an opening 21, designed as a ventilator, whereby the odors or heat from the milk may escape. The reservoir 10, as above set forth, is designed to be filled or

emptied through the opening 21, and the cap-section 20 is provided with a cover 22, which is secured to the cap-section 20 by a band or strap 23.

The reservoir 10 is provided with a cover 24, which is secured to the reservoir 10 by a band or strap 25. The cover 24 is provided with a handle 26, which is secured to the cover 24 by a band or strap 27.

The reservoir 10 is provided with a cover 28, which is secured to the reservoir 10 by a band or strap 29.

partly filled with water, so as to insure that the milk will be brought to the desired temperature in order that the best results may be attained.

5 By reference to the drawings it will also be seen that a faucet 22 is provided for the cap-section 7, whereby the liquid contents of the churn-body may be readily withdrawn after the butter has been produced. After 10 the water-reservoir has been placed in position in the flange 11, so that the spring 14 will bear against the end section of the body, the cap 7 is turned home, it being understood that the water-reservoir is properly filled with 15 the desired quantity of water or with water and ice. The desired quantity of milk to be churned is then introduced through the opening 19 and the churn placed in position upon the carriage, when by a proper rocking movement 20 the contents of the churn-body and the reservoir 10 may be caused to reciprocate or move from end to end of the churn, inducing great agitation of the milk by reason of the plurality of flanges 15. If it should become 25 desirable to introduce water into the milk, this may readily be accomplished by turning the reservoir 10 so as to bring the apertures 12 and 13 into registration with each other for a proper length of time, and after the desired 30 quantity of water has thus been permitted to escape said reservoir may be partially rotated so as to bring said apertures out of registration, thereby closing communication between the water and milk chambers.

35 As above set forth, any desired number of flanges 15 deemed productive of the best results may be employed. After proper agitation of the contents of the churn-body has thus been brought about said contents may 40 be readily examined by removing the closure

20, and if the churning process is found to be complete the liquid contents of the churn-body may be readily withdrawn through the faucet 22, leaving only the butter within the churn, which may be easily secured by removing the cap 7 and the water-reservoir 10. 45

In some instances I employ the bail 4^a, by which the churn-body 4 may be suspended, as from a rope or arm reaching down from the ceiling, as will be understood, and the 50 same rocking reciprocating motion may thus be readily imparted to the contents of the churn-body.

Believing that the advantages and manner of using my improved churn have thus been 55 made clearly apparent, further description is deemed unnecessary.

What I claim as new, and desire to secure by Letters Patent, is—

The herein-described churn, comprising a 60 suitable milk-reservoir, or body portion 4; a rocking support for said body portion; a suitable cap provided at one end of said body portion and a cup-like flange 11 at the opposite end, in combination with a water-reservoir 10, 65 the inner end of which is adapted to be received by said flange while the outer end is secured by said cap, thereby disposing the water-reservoir concentrically in the churn-body, said water-reservoir having a plurality 70 of radially-disposed agitating-flanges 15 and a cushioning-spring 14, all combined substantially as specified and for the purpose set forth.

In testimony whereof I affix my signature 75 in presence of two witnesses.

LYMAN C. MARTIN,
